(57) **CLAIM**

The ornamental design for a wall mount smart calendar display apparatus, as shown and described.

DESCRIPTION

FIG. 1 is a top perspective view of a wall mount smart calendar display apparatus showing my new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken line showing the back handle, table stands, camera holes, volume and power buttons, the corners, speaker holes and charging ports in FIGS. 1-8 is included for the purpose of illustrating environmental structure and forms no part of the claimed design.
